DESIGN FOR A COVERED PITCHER

John B. Ward, Corning, N. Y., assignor to Corning
Glass Works, Corning, N. Y., a corporation of
New York

Application June 11, 1945, Serial No. 120,012

Term of patent 14 years

(Cl. D44—21)

To all whom it may concern:

Be it known that I, John B. Ward, a citizen of the United States of America, residing in the city of Corning, county of Steuben, and State of New York, have invented a new, original, and ornamental Design for a Covered Pitcher, of which the following is a specification, reference being had to the accompanying drawing, forming a part thereof.

In the drawing:

Fig. 1 is a top plan view of a covered pitcher embodying my new design; and

Fig. 2 is a side elevational view of the same.

I claim:

The ornamental design for a covered pitcher, as shown.

JOHN B. WARD.
